UNITED STATES PATENT OFFICE

90,589

DESIGN FOR A CAMERA CASING

Joseph Mihalyi, Rochester, and Walter D. Teague, New York, N. Y., assignors to Eastman Kodak Company, Rochester, N. Y., a corporation of New York

Application June 24, 1933. Serial No. 48,528

Term of patent 7 years

To all whom it may concern:

Be it known that we, JOSEPH MIHALYI and WALTER D. TEAGUE, citizens of the United States of America, residing at Rochester, in the county of Monroe, and in New York city, in the county of New York, respectively, both in the State of New York, have invented a new, original, and ornamental Design for Camera Casings, of which the following is a specification, reference being had to the accompanying drawing forming a part thereof in which

Figure 1 is a front elevation of a camera casing showing our design.

Figure 2 is a top plan view of the camera shown in Figure 1.

Figure 3 is a rear elevation of the camera shown in Figure 1.

Figure 4 is an end elevation of the camera shown in Figure 1.

The cross lines in the drawing are not intended to represent color but to accentuate the contrast with the stripes and unlined portions which are preferably of finished metal and are for the purpose of illustrating different shades of intensities of the decorative panels.

We claim:

The ornamental design for a camera casing as shown and described.

Signed at Rochester, New York, this 20 day of June, 1933.

JOSEPH MIHALYI.
WALTER D. TEAGUE.
